UNITED STATES PATENT OFFICE

120,252

DESIGN FOR A RUG FABRIC

August Beck, Oshkosh, Wis., assignor to Waite
Carpet Company, Oshkosh, Wis., a corporation of Wisconsin

Application July 20, 1939, Serial No. 86,132

Term of patent 14 years

To all whom it may concern:

Be it known that I, August Beck, a citizen of the United States, residing at Oshkosh, in the county of Winnebago and State of Wisconsin, have invented a new, original, and ornamental Design for a Rug Fabric, of which the following is a specification, reference being had to the accompanying drawing, forming a part thereof, wherein, the figure shows a portion of a rug fabric embodying the design. The background is in the dull tones of paper twine, while the pattern stripes are in the intense glossy tones of sisal.

I claim:

The ornamental design for a rug fabric, as shown and described.

AUGUST BECK.
